NOSE PLUG

George C. Thurman, Peru, Nebr.

Application January 24, 1941, Serial No. 375,863

3 Claims. (Cl. 128—132)

The present invention relates to new and useful improvements in nose plugs particularly for swimmers and has for its primary object to provide, in a manner as hereinafter set forth, an appliance of this character which will positively prevent water from entering the nasal passages of the nose.

Another very important object of the invention is to provide an appliance of the aforementioned character embodying novel means for securing the device in position.

Still another important object of the invention is to provide a nose plug of the character described embodying unique means whereby the device may be expeditiously inserted and removed.

Other objects of the invention are to provide a nose plug of the character set forth which will be comparatively simple in construction, highly efficient and reliable in use, compact, inconspicuous, comfortable and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in side elevation, showing a device constructed in accordance with the present invention in use.

Figure 2 is a view in front elevation thereof, one of the plugs being shown in vertical section.

Figure 3 is a view in horizontal section, taken substantially on the line 3—3 of Figure 2.

Referring now to the drawing in detail, it will be seen that the embodiment of the invention which has been illustrated comprises a pair of substantially conoidal shell plugs 1 of suitable material, preferably resilient rubber. The resilient rubber plugs 1 are adapted to be inserted in the nostrils 2 of the nose 3. The resilient plugs 1 are of a shape and size to fit properly with maximum comfort.

It will be noted that the resilient plugs 1 are substantially hollow. Formed integrally with the plugs 1 and depending therefrom are stems 4. At their lower ends, the stems 4 terminate in laterally projecting integral arms 5 which are engageable with the vomer portions 6 of the nose 50 for securing the plugs 1 in position.

The plugs 1 are mounted on a resilient metallic connector which is designated generally by the reference numeral 7. The connector 7 includes an accurate bar 8 having substantially U-shaped projections 9 on its ends. It will be observed that the projections 9 diverge. Extending from the projections 9 are undulated legs 10 which are embedded longitudinally in the stems 4.

It is thought that the manner in which the

device functions will be readily apparent from a consideration of the foregoing. Briefly, to insert the appliance the resilient plugs 1 are introduced into the nostrils and the projections 9 of the resilient connection 7 are squeezed together between the thumb and index finger of one hand. Thus, the nibs or securing arms 5 are spread apart to facilitate insertion of the plugs 1 to the desired position in the nostrils 2. When properly positioned the projections 9 are released and the nibs or arms 5 are engaged by the resilient connector 7 on the vomer portion 6 of the nose in the manner suggested in Figure 2 of the drawing. The skirt portions of the resilient, conical plugs 1 engage the walls of the nostrils in a manner to prevent the passage of water. Of course, to remove the device the diverging projections 9 of the resilient connector 7 are again squeezed together for spreading the nibs 5 in a manner to clear the vomer 6.

It is believed that the many advantages of a nose plug constructed in accordance with the present invention will be readily understood and although a preferred embodiment of the device is as illustrated and described, it is to be understood that changes in the details of construction may be resorted to which will fall within the scope of the invention as claimed.

What is claimed is:

1. A nose appliance of the character described comprising a pair of conoidal shell plugs engageable in the nostrils, stems integral with the plugs and depending therefrom, means on the stems engageable with the vomer portions of the nostrils for releasably securing the plugs in position therein, and means for connecting the plugs.

2. A nose appliance of the character described comprising a pair of resilient conoidal shell plugs engageable in the nostrils, stems integral with the plugs and depending therefrom, means on the stems engageable with the vomer portions of the nostrils for releasably securing the plugs in position therein, and means for connecting the plugs, the last named means including a resilient bar, substantially U-shaped projections on the ends of said bar, and legs on said projections embedded in the stems.

3. A nose appliance of the character described comprising a resilient connector including an arculate bar, substantially U-shaped, diverging projections on the ends of said bar, integral legs on said projections, stems of resilient rubber mounted on said legs, substantially conoidal shell plugs of resilient rubber integral with one end of the stems and insertable in the nostrils, and laterally projecting nibs integral with the other ends of the stems engageable with the vomer portions of the nostrils for securing the plugs therein.

GEORGE C. THURMAN.
